UNITED STATES PATENT OFFICE.

SAMUEL MILLER, OF MOHAWK, NEW YORK, ASSIGNOR OF TWO-THIRDS TO
R. R. WIGHTMAN, OF ALBION, MICHIGAN.

DESIGN FOR A WEATHERBOARD.

SPECIFICATION forming part of Design No. 22,795, dated September 19, 1893.

Application filed August 26, 1893. Serial No. 484,156. Term of patent 7 years.

To all whom it may concern:

Be it known that I, SAMUEL MILLER, a citizen of the United States, residing at Mohawk, Herkimer county, State of New York, have invented and produced a new and original Design for a Weatherboard, of which the following is a specification, reference being had to the accompanying drawings, in which—

Figure 1 is a perspective view of a weatherboard showing my design. Fig. 2 is an edge elevation of a portion thereof.

The leading feature of the design is the raised panel surrounded by a beveled fluted border, the panels being arranged side by side, so that there is a scallop between the panels.

A is a raised panel, having a beveled border D, upon which is produced the fluting C. The panels are arranged end to end on the board, to produce the edge elevation shown in Fig. 2, the panels being separated by scallops or shallow grooves, fluted as shown. The panels are ornamented by an irregular series of points or cuts D.

What I claim is—

The design for a weatherboard herein shown and described.

SAMUEL MILLER.
